UNITED STATES PATENT OFFICE

2,001,536

INTERNAL COMBUSTION ENGINE

Franz Lang, Munich, Germany, assignor to
Lanova Aktiengesellschaft, Vaduz, Liechtenstein

Original application December 1, 1930, Serial No. 499,224. Divided and this application November 1, 1933, Serial No. 696,156. In Germany March 6, 1929

2 Claims. (Cl. 123—32)

My invention relates to a fuel injection internal combustion engine of the type which embodies an air storage chamber in which fluid is compressed during the compression stroke of the piston 5 ton and from which fluid issues during the working stroke of the piston.

This application is a division of my copending application, Serial No. 499,224, filed December 1, 1930, for Internal combustion engines.

10 The instant invention is directed to an improved air storage construction, to the end of obtaining ease in starting of the engine and assuring thorough mixing of the fuel charge in the operation of the engine.

15 In the drawing:—

Figure 1 is an axial sectional view through the outer end portion of a cylinder and the head thereof of an engine embodying my invention, parts being shown in elevation;

20 Figure 2 is a longitudinal sectional view through the air storage chamber, on an enlarged scale, parts being shown in elevation;

Figure 3 is a section taken substantially on line A—B of Fig. 2;

25 Figure 4 is a view similar to Figure 2, but showing a modified form of air storage chamber; and

Figure 5 is a section taken substantially on line C—D of Figure 4.

30 I have illustrated by invention, by way of example, as applied to an injection engine comprising a cylinder structure c, a head h therefor, and a piston p operating in the cylinder.

35 Head h and the adjacent end portion of the cylinder define a combustion chamber o. An injection nozzle n is suitably mounted in the head, and is disposed to inject fuel into chamber o. An air storage chamber a screws into a boss r at the side of the head, it being understood that any suitable number of air storage chambers may 40 be provided.

The chamber a comprises an outer cylindrical casing d and an inner flanged nozzle member e, in the form of a Venturi, which seats in boss r and is held therein by casing d, and a disc f held seated in member e by casing d. A stem s extends from disc f through a sleeve t extending centrally through casing d and connecting the inner and the outer end walls u and w, respectively, thereof. An arm g is suitably secured upon the outer portion of stem s, and a compression coil spring i is disposed about the stem and confined between arm g and a cup washer m which abuts a cotter pin k secured through stem s. Spring i holds disc f snugly against wall u of

casing d while permitting turning of the disc by means of arm g.

The air chamber a comprises a main chamber l, defined by casing d, and a preliminary chamber x, defined by disc f and the inner portion of member e. Disc f is provided with two ports f' and, when the engine is in operation, is turned into position to bring parts f' into register with ports u' in wall u. During the compression stroke of the piston p fluid from above the piston, mostly pure air, is forced into chamber a and there stored under high pressure. Injection of fuel may occur as the piston approaches upper dead center and may continue during a predetermined portion of the working stroke of the piston. As the piston moves down, air is ejected at high velocity through Venturi member e into the combustion chamber o. This creates high turbulence of the fuel charge and assures thorough intermixing of the fuel and the air, which contributes to smoothness and efficiency in operation of the engine.

10 The capacity of preliminary chamber x is such that the compression will be sufficient, as the piston approaches its position of greatest compression, to cause ignition of the fuel charge when the engine is cold. In starting, disc f is turned so as to move ports f' thereof out of register with ports u' of wall u and cut off communication between preliminary chamber x and main chamber l of the air storage chamber a. After the engine 15 is warmed up, disc f is turned into its normal position, rendering main chamber l available for air storage purposes, the total capacity of the storage chamber then being proper to assure most efficient operation of the engine in the 20 manner above described.

In the modified form of air storage chamber shown in Figures 4 and 5, a suitably shaped valve plate y is secured upon the inner end of stem s, which is mounted for turning movement in a thickened portion t' of the wall of casing d'. Valve plate y is provided with a port z which registers with port u' of wall u in the normal position of the valve. The operation of this form of air storage chamber is the same as that 45 of the air storage chamber shown in Figures 1 to 4, inclusive, and need not be set forth in detail.

What I claim is:

1. In combination in an injection engine, a cylinder and a head therefor, a piston operating 50 in the cylinder, an injection nozzle for injecting fuel into the combustion space of the cylinder, an air storage chamber comprising a Venturi member seating in said head and opening into said combustion space and a casing secured in 55

the head and abutting the outer end of said member, the inner end of said casing being closed by a ported wall, a ported valve at the inner side of said wall and defining with said wall and the outer portion of said Venturi member an air storage chamber of fixed capacity, said casing also defining an air storage chamber of fixed capacity, and means for adjusting the valve and thereby controlling communication between said chambers of said storage chamber.

2. In combination in an injection engine, a cylinder and a head therefor, a piston operating in the cylinder, an injection nozzle disposed to inject fuel into the combustion space of the cyl-

inder, an air storage chamber comprising a Venturi member opening into said combustion space and a casing extending from the outer end of said Venturi member and closed at its inner end by a ported wall, a ported valve at the inner side of said wall and defining with said wall and the outer portion of said Venturi member an air storage chamber of fixed capacity, said casing also defining an air storage chamber of fixed capacity, and means for adjusting the valve and thereby controlling communication between said chambers of said air storage chamber.

FRANZ LANG.
